UNITED STATES PATENT OFFICE.

CHARLES E. PIERCE, OF AVON, WASHINGTON, ASSIGNOR OF TWO-THIRDS
TO WILL A. LOWMAN AND W. T. ODLIN, OF ANACORTES, WASHINGTON.

DESIGN FOR A NUT-LOCK WASHER.

SPECIFICATION forming part of Design No. 32,360, dated March 20, 1900.

Application filed January 30, 1900. Serial No. 3,371. Term of patent 14 years.

To all whom it may concern:

Be it known that I, CHARLES E. PIERCE, a citizen of the United States, residing at Avon, in the county of Skagit and State of Washington, have invented and produced a new and original Design for a Nut-Lock Washer, of which the following is a specification.

This invention relates to a new and useful design for a washer of a nut-lock; and the essential feature resides in a frusto-conical body having a series of fingers continuous with the same converging plane of the body and surrounding a central opening.

In the drawings, Figure 1 is a perspective view of a washer embodying the features of the design. Fig. 2 is a transverse vertical section of the same.

The numeral 1 designates the body of the washer, which is frusto-conical in form and has a central opening 2. Extending upwardly

toward the opening 2 and forming a part of the body 1 are a series of inwardly-directed fingers 3, having the ends thereof straight and in planes at right angles to the direction of the said fingers, and thereby provide a ²⁵ broken wall for the said opening 2. The fingers continue in the same converging plane as the body.

Having thus described the invention, what I claim is—

The design for a washer of a nut-lock, herein shown and described.

In testimony that I claim the foregoing as my own I have hereto affixed my signature in the presence of two witnesses.

CHARLES E. PIERCE.

Witnesses:

W. T. ODLIN,
WILL A. LOWMAN.
